RACE STARTING GATE

John C. Purcell, New York, N. Y., assignor to Puett Electrical Starting Gate Corporation, New York, N. Y., a corporation of California

Application July 27, 1955, Serial No. 524,672

15 Claims. (Cl. 119—15.5)

This invention relates to an improvement in starting gates for race tracks, particularly for running horse races as distinguished from trotting races, and is an improvement over the construction disclosed in the Harris and Whann Patent 2,309,952, granted February 2, 1943.

One of the objects of the invention is to provide a novel opening mechanism for an electric starting gate wherein there is provided a retractable keeper which, when it is pulled to its retractable position, will not injure a horse moving in or out of the stall of said starting gate.

Another object is to provide a bolt forming one of the latching elements of each pair of doors, which bolt is provided with bearing means whereby to overcome friction when the other latching element is detached from the first mentioned latching element.

An additional object is to provide a tongue and groove secondary locking means in combination with the aforementioned latching elements.

Other objects will appear hereinafter throughout the specification.

In the drawings:

Figure 1 is an elevational view, partly broken away, of a starting gate having pairs of doors provided with the structure of the present invention;

Figure 2 is an enlarged isometric view of a pair of doors in closed position with the upper and lower portions of the doors broken away;

Figure 3 is an enlarged side elevation of one of the latching elements and the mounting means therefor;

Figure 4 is an enlarged front elevational view of the other latching element and the mounting means therefor and showing in full lines its engagement with the first latching element;

Figure 5 is an end view of the structure shown in Figure 4;

Figure 6 is a top view of the structure shown in Figure 4;

Figure 7 is a vertical sectional view taken on the line 7—7 of Figure 3; and

Figure 8 is an enlarged longitudinal sectional view, partly broken away, of the first named latching element.

Referring to the drawings in detail, and more particularly to Figures 1 and 2, the starting gate as a whole is designated by the letter A. It is provided with pairs of supporting wheels 10, with steering means for one pair of wheels, not shown, and a superstructure 12. Suspended from the superstructure are a plurality of partitions 14, each pair of partitions forming a stall for a horse.

Each stall is provided with a pair of doors or closure members 16. Such doors are pivotally mounted on pivots 18 to their partitions in the usual manner. The structures of the doors and their mountings is conventional.

As shown in Figure 2, each pair of doors forms a V when in closed position.

Each right door of the pair of doors is provided with a mounting plate 20 that may be welded or otherwise rigidly secured to its door. Bolted thereto is a secondary plate 22 which mounts the primary latching element or bolt 24. Plate 22 is provided with a housing 26 that allows sliding

2

movement of the bolt therein. Each bolt is provided with a projection 28 having a handle 30, and the housing 26 is provided with a pair of vertical slots 32 and 34 and a horizontal slot 36 connecting the vertical slots. The bolt is also provided with a notch 38 which will be described hereinafter.

Referring to the left door of each pair of doors, each is provided with a mounting plate 40 for mounting a magnetic holding means 42 and the secondary latching element 44. The magnetic holding means preferably comprises a pair of coils seen in Figure 2 and numbered 46 and 48. These are adapted to hold the secondary latching element in the full line position upon energization of the coils 46 and 48 and upon deenergization of said coils to permit the secondary latching element to drop to the dotted line position, as shown in Figure 4, and free the primary latching element 24.

Each magnetic holding means 42 is connected by electrical wiring 50 to a source of electric potential, such as a battery, shown at 86. The wiring 50 is preferably housed in metal tubing 52 when in Figure 1. A starter's switch is shown at 54, connected through battery 86.

The secondary latching element 44 is pivotally mounted by means of the pivot 56. A plate 58 is provided with a plurality of slots 60 whereby this plate may be adjustably held to the said mounting plate 40 by bolts 60. Located on the forward end of adjustable plate 58 is a latch lug 62 which is adapted to engage in the notch 38, as shown in Figures 4 and 6, when the doors are in closed position.

Referring again to the bolt 24, and particularly to Figures 2, 3 and 8, the forward end of the bolt 24 is provided with a reduced portion 64 having a plurality of circular grooves 66. Mounted on said reduced portion are spaced rollers 68, each having an inner groove 70. Grooves 66 and 70 provide raceways for the balls 72, and the entire assemblage is held in position on the said reduced portion 64 by the shoulder 74 at one end and by the washer 76 at the other end. The washer is held in position by the screw 78 that threadedly engages the end of the said reduced portion.

As shown in Figures 2 and 4, each secondary latching element is provided with an armature 80 and a depending lug 82.

In the operation of the pairs of doors, and assuming the doors are in open position, the starting switch is closed so as to energize each of the magnetic holding means 42 on the left door of each pair of doors. The doors are then closed manually either before or after the horses are lead into the stalls. In the former case, the horses are led in from the rear end of each stall. It is sometimes necessary, however, to back a horse into the stall, in which case, the pair of doors of that stall is allowed to remain in open position until the horse is in the stall.

After the doors are moved to closed position, the secondary latching element 44 is manually raised from the dotted line position shown in Figures 2 and 4 to the full line position shown in these figures, at which time it will be held in this position due to the magnetic attraction of the armature 80 by the magnetic holding means 42. At this time, the depending lug 82 is in engagement with the spaced rollers 68, and the latch lug 62 has engaged the notch 38, as shown in Figure 6.

When the circuit is broken, all of the pairs of coils of the several magnetic holding means are deenergized, thereby permitting the heavier end of the secondary latching element containing the armature 80 to drop to the dotted line position shown in Figures 2 and 4, thereby releasing the primary latching element. Each of the pairs of doors is incidentally swung to open position by biasing means such as springs, not shown. Such biasing means are conventional in the starting gate art.

Assuming the doors to be in open position and that

3

one or more horses are being backed into the starting gate, under these circumstances, the projection 28 is moved downwardly in slot 32, horizontally in slot 36 and vertically in slot 34 to hold the bolt or primary latching element 24 in its retracted position. In view of the fact that horses are highly excitable animals, particularly at the start of a race, unless some such arrangement is provided for retraction of the bolt when the doors are open, the horse, attempting to be backed into the stall, would be injured by the projecting end of this bolt.

The provision of the rollers 68 on the end of the bolt permits a quicker release than has heretofore been possible in opening the doors of starting gates, and such rollers prevent binding should a horse be pressing against the doors at the time the doors are released.

The latch lug 62, when in engagement with the notch 38 provides a secondary holding means for the doors. This secondary holding means prevents movement of one door relative to the other door in the direction of the arrow 84, as seen in Figure 6.

The term "anti-friction means" in the claims is intended to include any one of the following (on the end of the bolt 24), viz., grease alone, anti-friction rollers, or anti-friction balls.

The above description and drawings disclose a single embodiment of the invention, and specific language has been employed in describing the several figures. It will, nevertheless, be understood that no limitations of the scope of the invention are thereby contemplated, and that various alterations and modifications may be made such as would occur to one skilled in the art to which the invention relates.

I claim:

1. In a race starting gate, having at least one stall opening, oppositely pivoted doors adapted to close said opening when in closed position, latching means for said doors comprising a retractable bolt on one of said doors having an end portion extending beyond the swinging edge thereof when in extended position, a pivoted lug bearing latch on the other of said doors, the lug bearing portion being in engagement with the projecting portion of said bolt, said projecting portion having anti-friction means thereon.

2. In a race starting gate, having at least one stall opening, oppositely pivoted doors forming substantially a right angle when in closed position, adapted to close said opening when in closed position, latching means for said doors comprising a retractable bolt on one of said doors having an end portion extending beyond the swinging edge thereof when in extended position, a pivoted lug bearing latch on the other of said doors, the lug bearing portion being in engagement with the projecting portion of said bolt, said projecting portion having anti-friction means thereon.

3. In a race starting gate, having at least one stall opening, oppositely pivoted doors adapted to close said opening when in closed position, latching means for said doors comprising a retractable bolt on one of said doors having an end portion extending beyond the swinging edge thereof when in extended position, a pivoted lug bearing latch on the other of said doors, the lug bearing portion being in engagement with the projecting portion of said bolt, said projecting portion having anti-friction rollers thereon.

4. In a race starting gate, having at least one stall opening, oppositely pivoted doors forming substantially a right angle when in closed position, adapted to close said

4

opening when in closed position, latching means for said doors comprising a retractable bolt on one of said doors having an end portion extending beyond the swinging edge thereof when in extended position, a pivoted lug bearing latch on the other of said doors, the lug bearing portion being in engagement with the projecting portion of said bolt, said projecting portion having anti-friction rollers thereon.

5. In a race starting gate, having at least one stall opening, oppositely pivoted doors forming substantially a right angle when in closed position, adapted to close said opening when in closed position, latching means for said doors comprising a retractable bolt on one of said doors having an end portion extending beyond the swinging edge

15 thereof when in extended position, a pivoted lug bearing latch on the other of said doors, the lug bearing portion being in engagement with the projecting portion of said bolt, said projecting portion having side by side anti-friction roller means thereon.

20. 6. The starting gate as specified in claim 1 in which there is a magnetic means mounted on the said other of said doors for holding, when energized, said pivoted lug in engagement with said projecting portion of said bolt.

25. 7. The starting gate as specified in claim 2 in which there is a magnetic means mounted on the said other of said doors for holding, when energized, said pivoted lug in engagement with said projected portion of said bolt.

30. 8. The starting gate as specified in claim 3 in which there is a magnetic means mounted on the said other of said doors for holding, when energized, said pivoted lug in engagement with said projected portion of said bolt.

35. 9. The starting gate as specified in claim 4 in which there is a magnetic means mounted on the said other of said doors for holding, when energized, said pivoted lug in engagement with said projected portion of said bolt.

40. 10. The starting gate as specified in claim 5 in which there is a magnetic means mounted on the said other of said doors for holding, when energized, said pivoted lug in engagement with said projected portion of said bolt.

45. 11. The starting gate as specified in claim 1 in which said retractable bolt is provided with means for holding the same in extended or retracted position.

12. The starting gate as specified in claim 2 in which said retractable bolt is provided with means for holding the same in extended or retracted position.

50. 13. The starting gate as specified in claim 3 in which said retractable bolt is provided with means for holding the same in extended or retracted position.

55. 14. The starting gate as specified in claim 4 in which said retractable bolt is provided with means for holding the same in extended or retracted position.

15. The starting gate as specified in claim 5 in which said retractable bolt is provided with means for holding the same in extended or retracted position.
